F. APTEK.

REINFORCEMENT OF CLOTHES PEGS OR PINS.

APPLICATION FILED OCT. 22, 1917.

1,277,170.

Patented Aug. 27, 1918.

UNITED STATES PATENT OFFICE.

FRANK APTE, OF GEELONG, VICTORIA, AUSTRALIA.

REINFORCEMENT OF CLOTHES PEGS OR PINS.

1,277,170.

Specification of Letters Patent. Patented Aug. 27, 1918.

Application filed October 22, 1917. Serial No. 197,915.

To all whom it may concern:

Be it known that I, FRANK APTE, a subject of the King of Great Britain and Ireland, and a resident of the city of Geelong, 5 in the parish of Corio, county of Grant, State of Victoria, Commonwealth of Australia, and whose post-office address is 42 Villamanta street, in the said city of Geelong, have invented new and useful Im- 10 provements Relating to the Reinforcement of Clothes Pegs or Pins, of which the following is a specification.

This invention relates to domestic and laundry pegs or pins employed for the purpose of holding fabrics to a clothes line for drying or airing purposes. The form of peg commonly used for this purpose is composed of wood and comprises a body having a suitable head and two legs divided by a gullet 20 which permits the legs of the peg to be forced over the fabric which is to be attached to the supporting line. In use, pegs of the kind referred to have proved to be popular but their life is extremely limited due to 25 the splitting, partially or wholly, of the body upwardly from the crown of the gullet thus destroying the usefulness of the peg. Exposure to weather also tends to shorten the usefulness of a peg in this regard.

30 The object of the present invention is to reinforce pegs of the character described in order to lengthen the life of the pegs by preventing them from splitting as described and in addition to provide pegs the legs of 35 which will retain the preferred flexibility and therefore be of a more reliable character. The invention is applicable to new as well as to existing pegs and is so arranged that the reinforcement cannot in any manner 40 cause damage to the articles suspended.

Referring to the drawings which form a part of this specification:—

Figure 1 is a view of a clothes peg or pin of ordinary form having a square cornered 45 major gullet.

Fig. 2 is a view of portion of a peg in which the end of the major gullet is curved or rounded.

Fig. 3 shows a square cornered major gullet having a minor gullet at its inner end.

Fig. 4 shows a major gullet having a curved crown and a minor gullet.

Fig. 5 shows a minor gullet and a circumferential groove around the legs of the peg.

55 Fig. 6 is a perspective view of a reinforcing ring having two spike extensions which

are pointed or sharpened to be driven into the crown of the gullet.

Fig. 7 is a perspective view of a reinforcing ring having a long and a short extension in place of the spikes.

Fig. 8 is a perspective view of a reinforcing ring made in two pieces pivoted to each other one being provided with two right angled extensions.

Fig. 9 is a view similar to Fig. 8 except that the extensions are curved.

Fig. 10 is a part sectional side view of portion of the peg seen in Fig. 1 showing the reinforcing ring of Fig. 6 applied thereto.

Fig. 11 shows the application of the reinforcing ring seen in Fig. 7 to a peg having a circumferential groove but no minor gullet.

Fig. 12 shows portion of a peg having a two-piece reinforcing ring as seen in Fig. 8. The right angled extensions are accommodated by a minor gullet.

Fig. 13 shows a peg encircled by a two-piece reinforcing ring having curved extensions as in Fig. 9.

On reference to the drawings it will be seen that the peg has a head 2, a body 3, two spring legs 4, a major gullet 5, a crown 6 85 to said gullet and square corners 7 between the crown and the legs.

In Figs. 2 and 4 it will be seen that instead of the crown of the gullet having square corners it is curved as at 8 to strengthen the 90 peg at the root of the legs.

Formed in the crown of the square cornered gullet (Fig. 3) or the curved gullet (see Fig. 4) may be a minor gullet 9. The width of the said minor gullet as also its 95 height or depth will depend upon conditions. Preferably it has converging walls and a rounded crown as shown.

Around the legs of the peg and near the crown of the gullet may be formed a circumferential groove 11 to accommodate a reinforcing ring, indicated by the numeral 13 in Figs. 6, 7, 10 and 11.

This ring is constructed of a single strip of metal, preferably wire, one end of which 105 is turned to form a radial extension 15 from which extends a spike 17 having a sharpened point 19. The other end of the strip has a coil 21 wound around the extension 15. Beyond the coil is a spike 25 having a sharp- 110 ened point 26.

Instead of the radial extension 15 before

described having a spike extending therefrom it may have an upward extension 27 (Fig. 7), from which protrudes a side extension 29. At the other end of the wire is a 5 coil 31 from which extends a leg 35.

In a modification the reinforcing ring is made in two pieces pivotally connected to each other (see Figs. 8 and 9). These include a half ring 37 having at each end a 10 loop 39. Through each loop passes portion of a second half ring 41 having bends 43. Beyond each bend is an upward extension 45. From each upward extension protrudes a radial portion 47, one of the two portions 15 47 resting upon the other.

Instead of the second half ring 41 having upward extensions 45 and radial meeting portions 47 it may be provided with rounded extension 49 one of which rests upon the 20 top of the other as shown. Reinforcing rings of this type are adaptable to pegs of varying diameters.

It will be seen that the parts 17, 25 in Fig. 6, the parts 27, 29, and 35 in Fig. 7, the 25 parts 45 and 47 in Fig. 8 and the parts 49 in Fig. 9, act as limit stops to prevent the reinforcing ring being pushed too far up the peg and also form distance pieces which determine the position of the reinforcing ring 30 in relation to the crown of the legs.

To apply the reinforcing ring seen in Fig. 6 the legs of the peg are pressed together and the ring is slipped over their lower ends and pushed upwardly toward the crown of the 35 major gullet into which the sharpened points of the spikes are passed as in Fig. 10. Upon releasing the legs of the peg they spring outwardly and are gripped tightly by the reinforcing ring.

40 The modifications shown in Figs. 7 to 9 may be used either with an ordinary peg as in Figs. 1 and 2 or with a peg having a minor gullet or a circumferential groove or both a minor gullet and a groove in combination as seen in Fig. 5. When used with 45 a minor gullet the upstanding extensions or

legs of the ring are pressed into said gullet as seen in Figs. 12 and 13. The minor gullet 9 also serves to strengthen the peg by diverting the strain as it does from the corners 7 from which point the pegs are invariably found to split when in use.

Having now described my invention what I claim as new and desire to secure by Letters Patent is:—

55

1. A reinforcement for wooden clothes pegs or pins having spring legs and a gullet therebetween, consisting of a metal ring adapted to encircle said legs, and a stop device connected to said ring and disposed 60 diametrically of the same, and perpendicularly with respect to the plane thereof, said stop device being adapted to perpendicularly engage the crown of the gullet so as to prevent movement of the ring toward the 65 head of the peg after such engagement has been effected.

2. A reinforcement for wooden clothes pegs or pins consisting of a metallic ring formed in two pieces pivoted together, said 70 ring having means upstanding therefrom to limit its upward movement along the peg.

3. A reinforcement for wooden clothes pegs or pins consisting of a metallic ring formed in two pieces pivoted together, one 75 of said sections having each of its ends bent to form upward extensions and radial meeting portions, the ends of the other section being bent around the upward bends of the first section.

4. A reinforcement for wooden clothes pegs or pins consisting of a metallic ring formed in two pieces pivoted to each other, one of said sections having a curved upward extension at each end thereof, the ends of the 85 other section being bent around the first section at the base of said curved extensions.

80 In testimony whereof I affix my signature,

FRANK APTED.

Witness:

CECIL W. GLESTNER.
